US00D962367S

(12) **United States Design Patent** (10) Patent No.: **US D962,367 S**
(45) Date of Patent: ** *Aug. 30, 2022

(54) **GOLF CLUB HEAD**

(71) Applicant: **PARSONS XTREME GOLF, LLC**,
Scottsdale, AZ (US)

(72) Inventors: **Robert R. Parsons**, Scottsdale, AZ
(US); **Matthew T. Andrews**, Scottsdale,
AZ (US)

(73) Assignee: **PARSONS XTREME GOLF, LLC**,
Scottsdale, AZ (US)

(*) Notice: This patent is subject to a terminal disclaimer.

(**) Term: **15 Years**

(21) Appl. No.: **29/778,628**

(22) Filed: **Apr. 14, 2021**

Related U.S. Application Data

(60) Division of application No. 29/763,585, filed on Dec. 23, 2020, now Pat. No. Des. 919,722, which is a continuation-in-part of application No. 29/760,203, filed on Nov. 30, 2020, which is a continuation-in-part of application No. 29/755,703, filed on Oct. 22, 2020, which is a continuation-in-part of application No. 29/748,024, filed on Aug. 26, 2020, now abandoned.

(57) **CLAIM**

The ornamental design for a golf club head, as shown and described.

DESCRIPTION

FIG. 1 is a top perspective view of a golf club head;
FIG. 2 is a bottom perspective view of the golf club head of FIG. 1;
FIG. 3 is a front elevational view of the golf club head of FIG. 1;
FIG. 4 is a rear elevational view of the golf club head of FIG. 1;
FIG. 5 is a top view of the golf club head of FIG. 1;
FIG. 6 is a bottom view of the golf club head of FIG. 1;
FIG. 7 is a left side view of the golf club head of FIG. 1; and,
FIG. 8 is a right side view of the golf club head of FIG. 1. The broken lines shown on the drawings form no part of the claimed design.

1 Claim, 4 Drawing Sheets
